UNITED STATES PATENT OFFICE.

TRACY C. WELTMER, OF NEVADA, MISSOURI.

MATTRESS-PAD.

1,045,228.

Specification of Letters Patent. Patented Nov. 26, 1912.

Application filed January 22, 1910, Serial No. 539,559. Renewed October 14, 1912. Serial No. 725,733.

To all whom it may concern:

Be it known that I, TRACY C. WELTMER, a citizen of the United States, residing at Nevada, in the county of Vernon and State 5 of Missouri, have invented an Improvement in Mattress-Pads, of which the following is a specification.

My invention relates to improvements in mattress pads.

10 The object of my invention is to provide certain novel padding for a mattress which will enable a person to lie comfortably thereon and without the liability of acquiring bed-sores.

15 A further object of my invention is to provide adjustable padding mechanism for a mattress which can be adjusted to different positions to suit the different positions assumed by a person lying upon the mattress.

20 The novel features of my invention are hereinafter fully described and claimed.

In the accompanying drawings which 25 illustrate my invention Figure 1 is a perspective view of the preferred form of my invention, showing the pillow pad disposed with one member mounted upon the other. In this form of my invention the mattress cover and pads extend transversely only a 30 portion of the width of the mattress. Fig. 2 is a plan view of the form of my invention shown in Fig. 1, a portion of the mattress being broken away and the pillow pad being shown disposed in a position coöperating.

35 Fig. 3 is a vertical section on the dotted line $a-b$ of Fig. 5. Fig. 4 is a perspective view of a modified form of my invention in which the mattress cover and pads extend 40 transversely the full width of the mattress. Fig. 5 is a view partly in side elevation and partly in vertical section of the form of my invention shown in Fig. 1, showing the pillow pad folded and serving as a head rest.

45 Fig. 6 is a view similar to Fig. 5, the pillow pad being shown in a position coöperating with the other pads to serve as a back rest. Fig. 7 is an enlarged end elevation of a portion of the mattress and cover and one of the 50 devices by which the cover is detachably secured to the mattress. Fig. 8 is an enlarged, fragmental view of a portion of the mattress, mattress cover, and one of the pads, and one of the devices by which the pads are 55 detachably secured to the cover.

Similar characters of reference denote similar parts.

1 denotes the mattress and 2 a cover therefor having preferably, means for being detachably secured to the mattress. 60 Preferably opposite ends of the cover 2 have secured to them snap hooks 3, which are adapted to detachably engage respectively with rings 4, secured to opposite ends of the mattress 1.

65 A pillow pad is provided which is preferably flexibly connected to the cover 2, said pad comprising preferably two members 5 and 6, preferably flexibly connected at their adjacent side edges, as by the covering which 70 envelops said members, as shown in Fig. 3, and denoted by 7, whereby the members 5 and 6 may be swung from positions disposed one above the other, as shown in Fig. 1, to the position shown in Fig. 3, in dotted lines. 75

80 The members 5 and 6 are also preferably detachably and flexibly connected to the cover 2, at the points 8 and 9, whereby said members may be swung from the positions in which they form a head rest, to the positions shown in Fig. 2, in which they form a back rest. Secured upon the upper side of the cover 2, preferably by flexible connections located at the points 11 and 12, is a 85 pad 13, which is disposed in a position such that the pillow pad members 5 and 6, when swung to the positions shown in Figs. 2 and 6, will overlap it and coöperate with it to form a back rest.

90 Any suitable means may be employed for flexibly and detachably securing the pad members 5 and 6 and the pad 13 to the cover 2. As illustrated, the pad members 5 and 6 and the pad 13 may be provided at their edges with flaps 14, of flexible material, having respectively sockets 15, secured thereto and adapted to receive and releasably engage studs 16, which are secured to the cover 2. The sockets 15 and studs 16 may be of the ordinary glove fastener type. One of 100 these fasteners is shown in Fig. 8. If desired, a supplemental pad 15, may be disposed between the mattress 1 and the cover 2 below the pad 13, as shown in the drawings, when the pads are applied to an old mattress which has become depressed in the middle portions, as shown in Figs. 5 and 6, or when it is desired to have the back rest unusually high. 105

110 In the operation of my invention, when

the person desires to lie upon his back the pillow pad members 5 and 6 are disposed as shown in Figs. 2 and 6. If he desires to lie on his side he detaches the securing strap 14 of the member 6 from the cover 2 and swings the said member upon the member 5, as shown in Figs. 1 and 5, the members 5 and 6 prior to such detachment, having been swung from the position shown in Fig. 6 to the position shown in dotted lines in Fig. 1. The pad 13 will then fit into the hollow of the person's side and his head will lie upon the pad 6, as shown in dotted outlines in Fig. 5. With this arrangement of the pads a depression is provided between the pillow pad and the pad 13 to receive the shoulder of the person.

In the preferred form of my invention, shown in Figs. 1 and 2, in which the cover is substantially one half the width of the mattress if the person tires of lying upon the pads he can roll over upon the unpadded portion of the mattress 1.

If desired, the detachable cover 2 may be dispensed with.

My invention is particularly adapted for use by the sick or by those who by infirmities are bed ridden.

I do not confine my invention to the pre-

cise construction herein shown and described, as various modifications of it may be made, within the scope of the appended claims, without departing from its spirit.

Having thus described my invention, what I claim and desire to secure by Letters Patent, is:

The combination with a mattress cover, of a pad secured to the cover and adapted to afford a back rest, and another pad comprising two wedge shaped members flexibly connected to the cover at their bases between the first named pad and the adjacent end of the cover, one member being detachably connected to the cover, said members being flexibly connected with each other at the adjacent ends, whereby the two members may be swung on the cover so as to overlap the back rest, or swung one upon the other with their thickest portions one above the other and next to the first named pad, so as to serve as a pillow.

In testimony whereof I have signed my name to this specification in presence of two subscribing witnesses.

TRACY C. WELTMER.
